US0D1109996S

(12) United States Design Patent (10) Patent No.: US D1,109,996 S
(45) Date of Patent: * Jan. 27, 2026

(54) SHOE

(71) Applicant: NIKE, Inc., Beaverton, OR (US)
(72) Inventor: Lauren Sebastian, Portland, OR (US)
(73) Assignee: NIKE, Inc., Beaverton, OR (US)

() Term: 15 Years

(21) Appl. No.: 29/962,347

(22) Filed: Sep. 11, 2024

(51) LOC (15) Cl. 02-04

(52) U.S. Cl.
USPC D2/972

CLAIM

The ornamental design for a shoe as shown and described.

DESCRIPTION

FIG. 1 is a front perspective view of a shoe showing my new design;

FIG. 2 is a side view thereof;

FIG. 3 is a rear perspective view thereof;

FIG. 4 is a rear view thereof;

FIG. 5 is an opposite side rear perspective view thereof;

FIG. 6 is an opposite side view thereof; and,

FIG. 7 is an opposite side front perspective view thereof.

The broken lines immediately adjacent to the shaded area define the bounds of the claimed design and form no part thereof. The vertical broken line on the rear of the shoe represents a seam that forms no part of the claimed design. The broken lines depicting the remainder of the shoe form no part of the claimed design.

1 Claim, 7 Drawing Sheets
